UNITED STATES PATENT OFFICE.

EDWARD ADELL, OF ORANGE, MASSACHUSETTS, AND CARL A. BRINK, OF CRANSTON, RHODE ISLAND, ASSIGNEES TO UNIVERSAL WINDING COMPANY, OF BOSTON, MASSACHUSETTS, A CORPORATION OF MASSACHUSETTS.

COP OR BOBBIN HOLDER.

1,423,824.

Specification of Letters Patent. Patented July 25, 1922.

Application filed September 13, 1920. Serial No. 409,898.

To all whom it may concern:

Be it known that we, EDWARD ADELL, of Orange, in county of Franklin, State of Massachusetts, and CARL A. BRINK, of Cranston, in the county of Providence, State of Rhode Island, citizens of the United States, have invented certain new and useful Improvements in Cop or Bobbin Holders, of which the following is a specification.

10 This invention relates to improvements in cop- or bobbin-holders for braiding-machines and other textile apparatus.

The principal object of the invention is to provide a device of the type specified to 15 which the cop or bobbin may be more easily and conveniently applied and on which it will be more securely held to control its rotation in delivering the yarn or thread therefrom.

20 Another object of the invention is to provide a bobbin-holder which may be more readily placed on and removed from the spindles of the braider-carriers, whereby to facilitate the application of the bobbins to 25 the holder and the doffing of the empty cop-tubes therefrom.

Another object of the invention is to provide a bobbin-holder which may be constructed of sheet-metal to save weight and 30 economize in the cost of manufacture without sacrificing strength and staunchness.

Another object of the invention is to provide a bobbin-holder which will be proof against injury or breakage from careless 35 handling and otherwise more durable in use for the purpose described.

Further objects of the invention will appear from the description of the device set forth in the following specification and illustrated in the accompanying drawings in 40 which like reference-characters designate like parts. In the drawings:

Fig. 1 is a side elevation of the improved cop- or bobbin-holder;

45 Fig. 2, a vertical sectional view of the same taken in a plane coincident with its central axis and showing the cop-tube in place thereon;

50 Fig. 3, a horizontal sectional view of the holder taken on the line 3—3 of Fig. 2 and illustrating the manner in which it engages the interior of the cop-tube;

Fig. 4, a vertical sectional view of the inner tube of the holder showing a slight modification in its construction;

55

Fig. 5, a plan view of the end-head, or ratchet-disk of the holder showing it at the first stage in its construction;

Fig. 6, a sectional view of the same taken on the line 6—6 of Fig. 5;

60

Fig. 7, a plan view of the head at a later stage in its construction;

Fig. 8, a sectional view of the same taken on the line 8—8 of Fig. 7;

Fig. 9, a plan view of the head just previous to its completion; and

Fig. 10, a plan view of the finished head showing the other parts of the holder in connection therewith.

Our improved bobbin-holder is intended 70 for use particularly on braider-carriers having spindles on which the bobbins or cops are rotatably mounted to deliver their yarn under the control of suitable tension-devices. It is to be understood, however, that the 75 present improvements are also adapted to be applied to the spindles or mandrels of other textile apparatus, such for instance as winding machines. It is the usual practice to control the delivery of the yarn from 80 the bobbins on the braider-carriers by means of a pawl-mechanism which operates to permit an intermittent rotation of the bobbin-holder under the pull on the yarn. For this purpose the bobbin-holder is generally provided with a ratchet-disk or head with which the pawl co-operates and the present invention relates particularly to this type of holder.

Referring to the drawings, our improved 90 bobbin-holder comprises in general a tubular sleeve or mandrel 2 adapted for insertion in the bore of the tube on which the cop or bobbin is wound, and a ratchet-disk or head 3 mounted on the end of the sleeve. As a 95 novel feature of the present improvement we also provided an inner tube or sleeve 4 arranged concentrically within the outer sleeve 2 and serving as a bushing or bearing to adapt the bobbin-holder to rotate freely 100 on the spindle of the braider-carrier. The above named essential elements of the device comprising the outer sleeve 2, the ratchet-head 3 and the inner sleeve or bushing 4 are

preferably constructed from sheet-metal and united by an ingenious method of construction, whereby to provide a particularly staunch reinforced structure capable of resisting hard usage when the bobbin-holders are dropped or tossed about during their handling.

Referring to Figs. 5 to 9 inclusive, for convenience of description the ratchet-disk or head 3 may be considered the main element or base of the device since it serves as a foundation for the other parts which are attached thereto. The head 3 is preferably constructed from a circular blank B, see Fig. 5, which is cupped out, as illustrated in Fig. 6, to form a flaring rim or flange 5 surrounding its periphery. At the center of the head 3 is a circular opening 7 within which the inner tube 4 is held, and at the sides thereof are rectangular slots 8 adapted to receive suitable end-lugs 9 on the outer sleeve 2 which are riveted therethrough to secure the parts together in the manner as hereinafter more fully described. The blank B is also 25 punched or perforated with a series of circular holes 10 arranged concentrically of its axis and adapted for a purpose as later explained.

To form the ratchet teeth 11 on the head or disk 3 the rim 5 of the blank B is slit through at intervals and cut away from the main portion of the disk to provide ears 12 which are bent or folded around into substantially horseshoe shape, as shown in Fig. 35 7. As here illustrated, the ears 12 extend inwardly substantially radial with the axis of the disk and their ends are notched or cut away at the top to form lugs 13 of less depth than the main portion of the ears, see Fig. 40 8. At the next operation the ears 12 are bent or forced toward each other and folded into substantially parallel overlapping relation, as shown in Fig. 9. It will be noted that when the ears 12 are bent into this relation their end lugs 13 will be brought into register with the holes 10 in the disk 3. At the next operation the metal in the lugs 13 is crushed or extruded down through the holes 10, as shown in Figs. 2 and 10, thus 45 forming a bond or tie between the extremities of the ears and the main portion of the disk 3. Through this ingenious method of construction the ears 12 are firmly anchored to the disk at their inner ends, while their 50 outer folded portions are united to the periphery of the disk at the points where they join therewith. In this improved structure the double ears 12 form the reinforced radial teeth 11 projecting from the face of the 55 disk 3 to adapt them to be engaged by the pawl or detent which controls the rotation of the bobbin-holder in the manner and for the 60 purpose as well known in the art.

Referring now to Figs. 1, 2 and 3, the 65 outer sleeve or mandrel 2 on which the cop

or bobbin is held is preferably constructed from sheet-metal bent into tubular form and slotted at 15 along its sides to provide spring-members 16 which engage the interior of the cop-tube C. Any suitable number of spring-members or ribs 16 may be provided for this purpose and in the present drawings four are shown. The spring-ribs 16 are bowed outwardly from the cylindrical end portions 17 of the sleeve 2, see Fig. 2, and extend substantially parallel to the axis of the holder throughout substantially their full length. When the paper or fibre cop-tube C is slipped on over the sleeve or mandrel 2 the spring-members 16 are compressed slightly and at the same time their sharp edges 18, see Fig. 3, will bite into the bore of the tube C whereby to firmly grip the latter to secure the bobbin to the holder.

It has before been noted that one end of the sleeve 2 is provided with projecting lugs 9 and, as shown in Figs. 2 and 10, these are inserted through the slots 8 in the disk 3 and headed over to rivet the tube to the disk.

The outer sleeve or mandrel 2 is further held to the disk 3 by means of the inner tube or bushing 4 which serves as a reinforcing element in the manner as next explained. Referring to Figs. 2 and 4, the bushing 4 may be constructed from seamless drawn tubing or may be rolled from flat stock as herein shown. The main portion of the tube 4 is of appropriate size to adapt it to fit freely onto the spindle of the braider-carrier, but at its lower end the tube 100 is flared or belled outwardly to provide an enlarged mouth portion 19. At its upper end the smaller main portion of the tube is inserted through the axial hole 7 in the disk 3 while its lower enlarged end fits 105 closely within the end of the outer sleeve 2. After the tube 4 has been applied to position in this manner its ends are swaged or headed over at 20 whereby to secure it in place; and in this way the tube 4 serves as a tie and reinforcing element for the outer sleeve 2 and materially strengthens and stiffens the whole structure.

Midway the ends of the inner tube 4 is a stop-limit or rest 21 for the spring-members 115 16. The stop or rest 21 consists simply of an annular abutment or raised ring against which the spring-members 16 bear when they are compressed toward the axis of the holder. The abutment or annulus 21 is preferably formed by swaging out the metal of the inner tube 4 in a convex ring, as shown in Fig. 2, or if preferred a wire ring 22 may be applied to the periphery of the tube 4 as illustrated in Fig. 4. The purpose of this stop-ring or rest 21 is to limit the contraction of the spring-members 16 to prevent them from being bent inwardly to such an extent that they will fail to react to the outermost limits. It is well known that spring- 120 125 130

metal will flex and react to a certain extent, but beyond this limit it becomes set and loses its resilience, so that the stop-ring 21 is provided to prevent the spring-members from being contracted beyond the safe limit. The purpose of the enlarged bell or mouth 19 at the bottom of the sleeve 4 is to provide for an easier entrance for the end of the carrier-spindle S, which is shown by dotted lines in Fig. 2 to illustrate the manner in which the carrier is slid over it. By this provision the application of the bobbin-carrier to the spindle is rendered much easier and more convenient, tending to a saving in time and effort on the part of the operator. Stated briefly, the holders may be readily slipped onto and off from the spindles so that the cops or bobbins may be more readily applied thereto. This saves the operator from reaching in over the machine to apply the bobbin to the holder when the latter is less accessible than when held in the hand. This improvement is of particularly advantage in facilitating the doffing of the empty cop-tubes from the holders since they frequently stick and require considerable force to pull them off. Moreover, this method of applying the bobbins and doffing the tubes eliminates the danger of bending the spindles, which is to be avoided so that the holders will turn freely and run true thereon.

It will be observed that our improvement provides a bobbin-holder of particularly light yet staunch and rigid construction, capable of resisting rough handling and hard usage and proof against wear or deterioration. The end-head or ratchet-disk on the holder is much lighter in weight than the usual cast-iron ratchet, yet possesses the necessary strength and stiffness in its reinforced teeth. The outer sleeve of the holder provides a particularly efficient gripping-means for securing the bobbin in place on the holder and the resiliency of its spring-members is preserved from deterioration by the stop-ring or abutment which prevents them from being crushed out of shape. The inner tube forms a straight smooth bearing for the holder on its spindle, and in addition serves as a tie or strut to reinforce the whole structure. The several parts of the device are secured together by a novel method of construction which renders them mutually reinforced and strengthened, while the complete device is designed for economical manufacture to cheapen its cost.

Various modifications may be made in the form and arrangement of the parts of the device without departing from the spirit or scope of the invention, therefore without limiting ourselves to the exact embodiment herein shown and described, we claim:

1. In a cop- or bobbin-holder, the combi-

nation of an end-head, an outer sleeve rigidly attached to said head, and an inner tube extending axially throughout the length of the sleeve and secured to one end thereof and also secured to the head at its opposite end.

2. In a device of the type specified, the combination of a ratchet-head, an outer sleeve fixedly secured at one end to said head and provided with spring-members for engaging the cop-tube, an inner tube extending throughout the length of the sleeve, said tube united to the sleeve at one end and secured to the head at its opposite end.

3. In a cop- or bobbin-holder, the combination of a head, an outer cylindrical sleeve attached to the head at one end, and an inner tube extending throughout the length of the sleeve and secured fixedly to the head at one end and rigidly fastened to the sleeve at its opposite end, said tube being enlarged at one end to facilitate its application to the spindle on which it turns.

4. A cop- or bobbin-holder comprising an outer mandrel having longitudinal spring-members adapted to engage the bore of the cop-tube, and an inner tube extending axially throughout the length of the outer mandrel and provided with a peripheral abutment adapted to be engaged by the spring-members to serve as a stop to limit their contraction to prevent them from losing their reactive effect.

5. A cop- or bobbin-holder comprising a sheet-metal end-head provided with openings cut therethrough, an outer cylindrical sleeve having end-lugs riveted through the openings in the head, and an inner tube extending axially through the sleeve with one end riveted through a central opening in the head and the opposite end fitted within the end of the sleeve and swaged over its edge.

6. In a device of the type specified, the combination of a ratchet-disk formed with an axial opening, an outer sleeve riveted to the disk at one end and provided with longitudinally extending spring-members for engaging the cop-tube, and an inner bearing-tube extending axially throughout the length of the sleeve, said tube having one end swaged over the free end of the sleeve and its opposite end swaged through the axial opening in the disk.

7. A cop- or bobbin-holder comprising a cylindrical sleeve having longitudinal slits forming ribs which are bowed outwardly to adapt them to act as spring elements to engage the interior of the cop-tube, and an inner tube arranged concentrically within the outer sleeve extending throughout its length and provided with an annular abutment adapted to serve as a stop-rest for the spring-members to limit the extent of their contraction to prevent impairment of their resiliency.

8. A cop- or bobbin-holder comprising a mandrel for the cop-tube and a ratchet-disk on the mandrel constructed from sheet-metal with holes extending therethrough and having a peripheral rim cut away to form ears which are folded radially inward in opposed relation and united to the disk by portions of their metal extruded through the holes in the disk.
9. A cop- or bobbin-holder comprising a mandrel for insertion into the cop-tube and a ratchet-disk at one end of the mandrel, said disk constructed from a sheet-metal blank having openings cut therethrough and provided with a peripheral flange, the flange being slotted at intervals and cut away from the disk to form ears which are folded inwardly in overlapping relation, and lugs on the inner extremities of the ears engaging with the openings in the disk to provide an anchorage or tie for the ears.

In testimony whereof we affix our signatures.

EDWARD ADELL.
CARL A. BRINK.
